Claims priority, application Great Britain Feb. 19, 1960

5 Claims. (Cl. 242—128)

When yarns are drawn axially off the end of yarn packages or bobbins, for example when drawing yarns from a creel for warping, balloons are formed. The size of the balloons depends on the speed of draw-off but if it becomes too big the balloons may interfere with each other.

The purpose of the present invention is to restrain the formation of balloons in this way.

According to the present invention an anti-balloon device for attachment to the end of a yarn package or bobbin comprises a circular body having four axially tapering sections, arranged end to end and decreasing, in order, in length and in mean diameter, the outer sections having their larger ends outermost and the inner sections having larger ends of the same diameter joining each other and smaller ends equal in diameter to and joining the smaller ends of the outer sections so that the body has a continuous undulating surface, and a ring surrounding the junction between the smaller ends of the two smaller sections, the dimensions of the four sections of the body being such that as a thread is drawn in a coiled path over the surface of the body, in passing over the largest section the circumferential component of the velocity of the thread is less than its axial velocity, in its movement over the second section its circumferential component is greater than its axial component and in its movement over the fourth and last section its circumferential component is again less than its axial component, the axial component of the velocity of the thread over the last section being greater than the axial component of the velocity over either of the first two sections.

Preferably the sections of the body are all frustoconical in shape. The ring should be a close fit around the body but it should be free to rotate on the body when the thread is drawn off through it. For use with some yarns particularly natural fibres and high-twist rayon the ring is preferably made of a soft resilient fibrous material such as felt. For use with most other synthetic yarns a ceramic or metal ring is better. In use the larger end of the circular body is attached coaxially to the end of the yarn package or bobbin and the yarn is drawn off axially over the surface of the body. The yarn is threaded between the ring and the part of the circular body which it surrounds and it then passes through an outlet eyelet which is arranged on the axis of the yarn package or bobbin a short distance away from the smaller end of the body.

As the yarn is drawn through the eyelet it automatically takes up a position in which it makes approximately one and a half turns around the circular body. These turns are opened out from each other in the form of a helix so that the yarn lies along the surface of all four conical portions of the body at an inclination to its axis. The ring is necessary to hold the yarn against the body in the place where the yarn passes through the ring, otherwise the yarn will not maintain contact with the body near its smaller end.

As the yarn is drawn over the surface of the body it has two components of velocity, one circumferential and one axial, over the surface of each of the conical portions. Although the resultant velocity must of course be constant these components vary over the various portions of the body in dependence upon the angle of in-

2

clination of the thread to the axis of the body. The thread is restrained by its frictional contact with the surface of the body and in this way is prevented from ballooning. A frictional drag is also exerted on the thread by its contact with the surface of the body and this provides the necessary back tension on the thread as it is drawn off from the package or bobbin. This is a further considerable advantage of the device because it makes the usual form of tensioning device, which consists of two plates pressed together by a spring and between which the yarn passes, unnecessary.

An example, and a modification of this example, of a device in accordance with the invention mounted in position on the end of a yarn package on a creel is illustrated in the accompanying drawings, in which:

FIGURE 1 is a side elevation of the device and its mounting with the yarn package shown diagrammatically;

FIGURE 2 is a similar side elevation of the device by itself without the ring shown to a larger scale; and

FIGURE 3 is a sectional detail showing a modification of smaller end of the body.

As shown in FIGURE 1 the angle sections 1 and 2 shown in chain dotted lines form part of the frame of a creel and on it a very large number of yarn packages are mounted from which threads may be drawn for winding on to a warp beam or for other purposes.

A circular rod 3 passes through holes in the two angle sections 1 and 2 and over its free end the tube 4 of a yarn package 5 is placed. The yarn package 5 is held in position against the angle section 1 by an anti-balloon device 6 which is screwed on to a thread 7 on the end of the rod 3. The anti-balloon device 6 has a body consisting of four truncated conical sections 8, 9, 10 and 11. These four sections are made as a single die casting.

In this particular example the dimensions *a* to *k* of the various sections 8 to 11 of the device, as shown in FIGURE 2 of the drawings, are as follows.

	inches
<i>a</i>	1 1/32
<i>b</i>	1 1/32
<i>c</i>	5/8
<i>d</i>	3/4
<i>e</i>	5/16
<i>f</i>	3/8
<i>g</i>	7/8
<i>h</i>	1
<i>i</i>	1
<i>j</i>	1 1/16
<i>k</i>	3/8

A felt washer 12 surrounds the neck at the junction between the sections 10 and 11 of the device. The diameter of the hole in the washer 12 is only slightly greater than *e* so that it is a snug fit. Because of the elasticity of the felt, the washer 12 can be placed in position by pushing it over the section 11. In use the yarn 13 from the package 5 is passed through the central hole in the washer 12 and thence through an eye 14 which is fixed to the frame of the creel so that its centre lies on the extended axis of the package 5. When the yarn 13 is drawn through the eye 14 it automatically takes up a position as shown in FIGURE 1 in which it makes approximately one and a half full turns around the device 6. Slightly less than one half of a full turn takes place over each of the sections 8 to 10 and approximately a third of a full turn takes place over the section 11. As the yarn 13 is withdrawn through the eye 14, when for example it is wound on to a warp beam, the yarn is dragged over the surface of the device 6 and the path which it travels over this device rotates around it.

The velocity of the yarn 13 must of course be constant along its length since it is not stretched; but the compo-

nents of its velocity in a circumferential direction around the device 6 and in an axial direction parallel to the axis of the yarn package 5, vary over each of the sections 8 to 11.

In passing over the section 8, as shown in FIGURE 1 of the drawings, the yarn has a circumferential component of velocity C_1 and an axial component A_1 . In passing over the section 9 these components are C_2 and A_2 respectively and in passing over the section 11 these components are C_4 and A_4 . With the dimensions shown in the drawings these velocity components bear the following relationship to each other. C_1 is less than A_1 , C_2 is greater than A_2 and C_4 is less than A_4 , but A_4 is greater than A_1 or A_2 . When these ratios apply the yarn remains over its whole path in contact with the various sections of the device 6 and has no tendency to be drawn outwards to form a balloon.

The exact dimensions of the device 6 will of course depend upon the size of the yarn package 5 with which it is to be used, but the proportions shown in the drawings should preferably be maintained. All that is essential, however, is that the proportions should be such that the velocity ratios just given are obtained.

In the modification shown in FIGURE 3 the felt washer 12 is replaced by a ring 15 made of ceramic material. Because this material is not elastic as is felt it cannot be placed in position over the end of the section 11'. Therefore as shown the section 11' is made separately from the section 10' and the two sections are detachably fixed together by a bolt 16 which passes through a bore 17 in the section 11' and is screwed into a tapped bore 18 in the section 10'.

Besides preventing the formation of a balloon and providing a back tension on the yarn the device in accordance with the invention has also the following advantages.

It is self-cleaning insofar as there is no surface for the collection of dirt, dust or lint, due to the self-wiping action of the yarn passing over the surface of the body. This is a great improvement over the usual type of tensioning device already described in which lint or dust and dirt tend to collect very rapidly between the two spring-pressed plates. Further the device does not therefore tend to cause the yarn to untwist or cause any broken filaments in the yarn to run back as the yarn is drawn off. When the yarn is drawn off at very high speeds of the order of 250 yards per minute and there is deceleration of draw-off, the device restricts any tendency for turns of the yarn to slough off the package or bobbin. This tendency is prevented because the momentum of the thread passing over the surface of the body is immediately absorbed by the frictional drag on the body, whereas in previous cases where there is a free balloon, this momentum is not absorbed and does tend to unwind extra turns. This advantage is of great importance with high-twist yarns which because of their twist are known to be "lively." That is to say, they are very prone to twist and throwback upon themselves and so become entangled with themselves or with adjacent yarns if the rate of draw-off is suddenly altered.

I claim:

1. In apparatus for drawing a thread from a package during warping and other thread winding operations, said apparatus including a support for said package and means for drawing said thread off said package in an axial direction, the improvement which consists of a device for reducing the ballooning of said thread as it is drawn off, said device comprising a circular body coaxially attached to the end of said yarn package and having two outer and two inner axially tapering sections having larger and smaller ends, said sections being arranged end to end and successively decreasing in length and in mean diameter in a direction away from said yarn package, said two outer sections having their larger ends outermost and said two inner sections having their larger ends of the same diameter and joining each other, the

adjacent smaller ends of each pair of adjacent inner and outer sections being of the same diameter and joining each other, so that the surface of said body is continuous and undulating in an axial direction, said device also comprising a ring for holding said thread against said body, said ring surrounding the junction between the smaller ends of the two smaller sections, the axial and transverse dimensions of each of said four sections being so related that as a thread is drawn off said yarn package in a coiled path over said surface of said body, in passing over the first and largest of said sections the circumferential component of the velocity of the thread is less than the axial component of said velocity, in its movement over the second of said sections the circumferential component is greater than the axial component and in its movement over the fourth and smallest of said sections the circumferential component is again less than the axial component, said axial component of the velocity of the thread over said smallest section being greater than said axial component of the velocity over either of said first two sections.

2. A device according to claim 1, in which each of said sections is frusto-conical in shape.

3. A device according to claim 2, in which said relative dimensions of said four sections are such that if the axial length of said smallest, fourth frusto-conical section is designated c and the diameter of its smaller end is d ; then the larger end diameter of this section is substantially $1.2d$, said third section has a length of substantially $1.3c$, a smaller end diameter of d and a larger end diameter of substantially $2.25d$, said second section has a length of substantially $2c$, a larger end diameter of substantially $2.25d$ and a smaller end diameter of substantially $1.9d$ and said first and largest section has a length of substantially $3.6c$, a smaller end diameter substantially $1.9d$ and a larger end diameter of substantially $4d$.

4. In apparatus for drawing a thread from a package during warping and other thread winding operations, said apparatus including a support for said package and means for drawing said thread off said package in an axial direction, the improvement which consists of a device for reducing the ballooning of said thread as it is drawn off, said device comprising a circular body coaxially attached to the end of said yarn package and a ring encircling said body to hold said thread thereagainst, said body being formed of a plurality of sections successively decreasing in length and in mean diameter in a direction away from said yarn package, alternate sections having gradually increasing diameters whereas the remaining sections have gradually decreasing diameters, the adjacent ends of each pair of adjoining sections being of the same diameter, the axial and transverse dimensions of each of said sections being so related that as a thread is drawn off said yarn package in a coiled path over the surface of said body, in passing over the largest section of decreasing diameter the axial component of the velocity of the thread is greater than its circumferential component, whereas in passing over the next largest section the axial component is less than the circumferential

component, and in passing over the smallest section of increasing diameter the axial component is again greater than the circumferential component over said last mentioned section and also greater than the axial component over either said largest section of decreasing diameter or said next largest section, the junction between the smallest section of increasing diameter and the next smallest section being closely encircled by said ring.

5. In apparatus for drawing a thread from a package during warping and other thread winding operations, said apparatus including a support for said package and means for drawing said thread off said package in an axial direction, the improvement which consists of a device for reducing the ballooning of said thread as it is drawn off, said device comprising a circular body coaxially attached to the end of said yarn package and a ring encircling said

body to hold said thread thereagainst, said body being formed of a plurality of sections successively decreasing in length and in mean diameter in a direction away from said yarn package, alternate sections having gradually increasing diameters whereas the remaining sections have gradually decreasing diameters, the adjacent ends of each pair of adjoining sections being of the same diameter, the axial and transverse dimensions of each of said sections being so related that as a thread is drawn off said yarn package in a coiled path over the surface of said body, the axial component of the velocity of said thread becomes successively greater, smaller, and then greater

than the circumferential component of said velocity, said axial component becoming greatest at a point near the end of said body remote from said package, and the junction between at least one section of decreasing diameter and a smaller section of increasing diameter being closely encircled by said ring.
